UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

TRACK-FASTENING FOR RAIL-JOINTS.

1,118,832.

Specification of Letters Patent.

Patented Nov. 24, 1914.

Application filed August 1, 1910. Serial No. 574,928.

To all whom it may concern:

Be it known that I, BENJAMIN WOLHAUPTER, a citizen of the United States, residing at New Rochelle, in the county of 5 Westchester and State of New York, have invented a certain new and useful Improvement in Track-Fastening for Rail-Joints, of which the following is a specification.

This invention relates to the subject of 10 railway track fastenings, and more particularly to that type of fastenings employed for securing the rail-joints of a track to the ties.

To this end the invention contemplates a 15 simple, but thoroughly practical and strong, fastening means so combined with the rail-joint parts as to provide for securing the rail-joints of a track to the ties in a much more secure and permanent manner than 20 is now possible with the ordinary forms of track fastenings for rail-joints.

In this connection a further and important object of the present invention is to 25 increase the efficiency of the screw spike or lag screw as a track fastening, particularly in its employment for securing rail-joints to the ties.

With these and other objects in view, which will more readily appear to those 30 familiar with the art as the details of the invention are better understood, the same consists in the novel construction, combination and arrangement of parts herein- 35 after more fully described, illustrated and claimed.

The essential features of the invention, involved in carrying out the objects above indicated are necessarily susceptible of a wide range or structural modification, according to the kind of joint to which the 40 invention is applied, without departing from the spirit or scope thereof, but certain preferred and practical embodiments are illustrated in the accompanying drawings, in which—

Figure 1 is a sectional end view of a rail-joint secured to a tie by a track fastening constructed in accordance with the present invention. Fig. 2 is a similar view illustrating a modification of the improved track fastening and showing the same associated with one of the bars of a rail-joint. Figs. 3, 4 and 5 are similar views illustrating further modifications in different features of the track fastening, and particularly adapted to be employed in combina-

tion with the screw spike or lag screw arranged in a vertical or substantially vertical plane. Fig. 6 is a sectional end elevation of a rail joint of the type shown in Fig. 1, and illustrating a modification wherein the screw spike is arranged obliquely or at an inclination from the perpendicular. Fig. 7 is a detail view illustrating a modification, showing another construction wherein the screw spike may be arranged obliquely.

Like references indicate corresponding parts in all the figures of the drawing.

In carrying out the present invention the essential and distinguishing features thereof are applicable to the various types of rail-joints now in use, though more particularly available for effective service with those kinds of rail joints which include in their general organization an angle bar and a base plate, which base plate, however, may be one of the elements of the rail-joint proper, or may be an ordinary tie plate underlying the rail where the rail-joint is located. While capable of this general application, the improved fastening means claimed herein are shown in the drawings, for illustrative purposes, as applied to certain standard forms of rail-joints, and particular reference will be made thereto in describing the construction claimed.

In the embodiment of the invention shown in Fig. 1 of the drawings the same is illustrated as applied to a standard joint of the well-known Weber type, which type of joint embraces, in combination with the rail R, an angle bar 1, an outer channel bar 2 at the side of the rails opposite the angle bar 1, an angle-shoe 3, and a filler block 4 interposed between the upright member of the shoe and the outer channeled side of the channel bar 2. In this form of joint the angle-shoe 3 includes a base plate 5 extending entirely beneath the rail bottom and projecting at its inner edge beyond the inner edge 6 of the rail flange.

According to the present invention the foot portion 7 of the angle-bar overlies the rail flange in the usual way, but has formed therewith an outward fastening flange-extension 8 projecting materially beyond the inner edge 6 of the rail flange, and having formed therein the spike hole 9 for the reception of the screw-spike 10, which extends through that hole and also through a spike hole 11 provided in the inner edge

portion of the base-plate 5, and beneath the base-plate the said screw spike engages in the tie in the usual manner.

In the construction shown in Fig. 1 the 5 outstanding flange-extension 8 lies in a substantially horizontal plane, and the screw spike 10 is arranged substantially perpendicular, and to provide a bearing contact between the head member 12 of the spike 10 and the upper side of the said flange-extension 8, the latter is formed at its upper side with a beveled channel 13, which produces a dished or beveled bearing seat in which registers the beveled or conical bearing face 14 formed upon the under side of the said head member of the spike. It will be observed, in connection with this construction, that the screw spike passes vertically 15 through the foot of the angle bar and also through the inner edge of the base plate 5, while at the same time bearing directly 20 against the rail-flange at 6. This brings the inner side of the spike head 12 above and over the inner edge portion of the rail flange, 25 thus giving a direct vertical pressure on the inside of the rail flange with the result of very securely holding the rail down in its proper place.

A modification of the construction shown 30 in Fig. 1 is suggested in Fig. 2, wherein it is proposed to omit the beveled bearing seat 13 at the upper side of the flange extension 8 and instead thereof provide the latter with a flat upper side 15 upon which bears the flat underside 16 of a washer 17. This washer has formed in its upper side a beveled or tapering bearing seat 18 within 35 which registers the conical under face 14 of the spike head 12. In this modification the spike hole 9 in the flange-extension 8 is made sufficiently large to provide an ample clearance for the spike therein so as to allow for any adjustment of the angle-bar 1 by the tightening of the joint bolts without 40 the necessity of moving the screw spike.

The modification above described, and 50 illustrated in Fig. 2, involves an advantage over the construction shown in Fig. 1 in that the employment of the washer 17 bearing flatly on the flange-extension 8 admits of the tightening of the joint bolts without affecting the bearing of the screw spike over the angle-bar extension 8, as it will be understood that as the bolts are tightened and 55 the angle-bar 1 is drawn inward in the direction of the arrow shown in Fig. 2 the under surface of the spike head continues to have complete and solid bearing at all 60 sides in the seat 18 of the washer 17.

In the modification suggested in Fig. 3 65 of the drawings there is proposed the expedient of omitting the washer 17 of Fig. 2, and forming the head 12 of the screw spike with a flat under side or bearing face 19 which flatly contacts with the flat upper

face 15 of the flange-extension 8. In other respects the construction shown in Fig. 3 is the same as that shown in Fig. 2, and admits of the angle-bar being tightened by the bolts 70 without affecting the continuous and uniform bearing under the head of the screw spike.

In further exemplification of the invention there is shown in Fig. 4 of the drawings a modification embodying the same 75 form of contact between the spike head and flange-extension, as shown in Fig. 3, but embodying the further feature of forming the flange-extension 8 with a depending toe-piece 20 having a beveled or inclined under surface 21 having a bearing contact with a correspondingly beveled or inclined surface 22 formed upon the edge portion of the base-plate 5. In this form of the invention the toe-piece 20 projects below the 80 plane of the edge 6 of the rail flange. By reason of providing this direct contact and engagement between the outer part of the flange-extension 8 and the base plate 5, the outer portion of the head of the screw spike is given a solid metallic support directly 85 from the base plate, which is a feature of practical importance in a track fastening of this character. Furthermore, the beveled surface 22 is preferably inclined at an angle 90 equal to the angle of incline of the top surface of the rail flange, and consequently any inward movement of the angle-bar does not affect the solid bearing engagement between the flange-extension 8 and the base 100 plate.

A further carrying forward of the invention is shown in Fig. 5 wherein all of the structural features and advantages of the construction shown in Fig. 4 are preserved, the only material difference being that Fig. 5 suggests the expedient of elevating the inclined surface 22 on the base plate to meet the correspondingly beveled or inclined face 21 on the flange-extension, as will be obvious 105 from an inspection of the two figures of the drawings.

The forms of the invention so far described have been directed to constructions wherein the flange-extension 8 lies in a substantially horizontal plane. This may be altered, as, for instance, by using the form of construction shown in Fig. 6. In the latter form of construction the flange-extension is designated by the reference letter 8^a, and is illustrated as being set at substantially the same inclination as the foot portion 7 of the angle bar above the rail flange. However, the said flange-extension is constructed at its upper side like the flange extension 8 shown in Fig. 1, and subserves all of the functions of the latter, but in the modified structure shown in Fig. 6 the screw spike is set at an angle to the perpendicular.

As a modification of the construction

shown in Fig. 6 there is shown in Fig. 7 the feature of providing the flange extension 8^a with the flat upper surface 23 with which flatly contacts the flat under face 24 of the head 12 of the screw-spike 10. This modification also includes the feature of the spike-hole 9 being of ample dimensions so as to accommodate the adjustment of the angle-bar 1 without disturbing the complete and solid bearing of the spike-head upon the flange-extension. In this form of construction, as well as in the forms of construction shown in Figs. 2 to 5, inclusive, it is only necessary, after adjustment of the angle-bar, to screw the spike into the tie to maintain the solid and uniform bearing for the spike-head, as above referred to. Furthermore, in the form of the invention shown in Figs. 6 and 7 of the drawings, the shank of the spike 3 has a direct bearing or engagement against the rail flange in substantially the same manner and for the same purpose as in the other forms of the invention.

I claim,—

1. In a track fastening for rail joints, the combination of a rail joint including a rail supporting base plate having an edge portion projecting beyond an edge of the rail flange and formed with an opening therein, and an angle bar whose foot is provided with an outwardly projecting flange extension having a spike hole therein and provided on its upper surface with a spike head seat, and a screw spike extending through the holes in said flange extension and said edge portion of the base plate, the head of said spike having a direct symmetrical bearing engagement at its under side with the said spike head seat.

2. In a track fastening for rail joints, the combination of a rail joint including a shoe angle whose rail supporting base plate projects beyond one edge of the rail flange and has formed therein a spike hole, an angle bar whose foot is provided with an outwardly projecting flange extension having a spike hole therein and a spike head seat on its upper surface, a compressible filler arranged at the inner side of the upright member of the shoe angle, and a screw spike extending through the holes in said flange extension and said base plate, the head of said spike having a direct bearing engagement at its under side with said spike head seat.

3. In a track fastening for rail joints, the combination of a rail supporting base plate having an edge portion projecting beyond an edge of the rail flange and provided therein with a spike hole, and an angle bar whose foot is provided with an outstanding flange extension having a direct bearing on said edge portion of the base plate at the same angle as the adjacent rail flange, said angle bar flange extension also having a spike hole therein, and a screw spike adapted to extend through the spike holes in said flange extension and said edge portion of the base plate, the head of the screw spike having a symmetrical bearing engagement at its under side with the top surface of said flange extension.

In testimony whereof I hereunto affix my signature in the presence of two witnesses.

BENJAMIN WOLHAUPTER.
